UNITED STATES PATENT OFFICE

WIRT D. RIAL, OF WATSON, CALIFORNIA

PROCESS OF REFINING LUBRICATING OILS

No Drawing.

Application filed February 13, 1929. Serial No. 339,738.

This invention relates to a process of refining lubricating oil stocks derived from petroleum oils, and while not necessarily confined thereto, it refers more particularly to the refining of lubricating oil stocks derived from an asphalt or mixed base crude petroleum oil, such as is found in California, Mexico, Texas, Russia and other countries. The lubricating oil stocks derived by distillation of an asphalt or mixed base crude petroleum oil contain high percentages of carbocyclic hydrocarbons of the naphthenic series in addition to certain undesirable percentages of sulphur bearing hydrocarbons, unstable unsaturated hydrocarbons and oxygenated products.

These sulphur bearing hydrocarbons, unstable unsaturated hydrocarbons and oxygenated hydrocarbons must be separated as completely as possible from the more stable hydrocarbons in order to produce a lubricating oil of high quality.

By well-known methods, the treating of lubricating oil stocks derived from an asphalt or mixed base crude petroleum oil requires the use of relatively large amounts of sulphuric acid, caustic soda and a final decolorizing treatment with a decolorizing agent, such as Florida fuller's earth, acid-treated montmorillonite, magnesium silicate and the like. By such treatments the lubricating oil stock produced, although purified to a comparatively high degree, may contain small percentages of impurities such as oxygenated hydrocarbons in sufficient amounts to emulsify with water when employed in steam turbines or for other lubricating purposes where the oil comes into contact with steam or water.

I am aware that certain methods are now known whereby lubricating oil stocks from an asphalt or mixed base crude petroleum oil may be specially treated to eliminate these impurities, but such processes involve either the use of expensive re-agents such as alcohol and the like, or other such methods which result in low yields.

Now, I have discovered a process whereby these difficulties may be overcome and a high grade lubricating oil produced which will

not emulsify when commingled with water, steam, or a water solution of caustic soda and one which can be employed for any kind of lubrication without further special treatments.

An object of the invention is to refine lubricating oil stocks derived from an asphalt or mixed base petroleum oil so as to economically produce a treated oil which will not emulsify and commingle with water or a water solution of caustic soda. 55

Another object of the invention is to produce a lubricating oil suitable for lubricating steam turbines or other machinery.

Another object of the invention is to produce a lubricating oil of high purity and substantially free from emulsifying constituents. 65

Another object of the invention is to produce a high grade lubricating oil substantially free from resins, gums, organic acids, phenols, organic sulpho-acids, unstable unsaturated hydrocarbons and corrosive sulphur-bearing hydrocarbons. 70

Another object of the invention is to accomplish the above with a minimum loss in 75 the final yield of the lubricating oil stock.

Other advantages of the invention will appear in the practical use of the same and from the following description.

For illustration, lubricating oil distillate 80 derived by fractional distillation, at a reduced pressure, from an asphalt base residuum or fuel oil from which the lower boiling oils have been separated, is continuously discharged into re-run stills and therein continuously subjected to a second distillation at a reduced pressure, care being taken that no air comes into contact with any of the products of distillation. 85

The vaporized products from the re-run 90 stills are condensed, allowing no contact of air therewith, and immediately subjected to a pressure treatment with a water solution of potassium hydroxide in the presence of steam which is employed to commingle the lubricating oil stock and the water solution of potassium hydroxide. This operation is carried out in accordance with the process as given in the pending application of John C. Black and Wirt D. Rial, Serial No. 187,110, 100

filed April 27, 1927, process of refining lubricating oils, which comprises treating lubricating oil stocks or distillates with a water solution of potassium hydroxide, agitating with steam under a pressure greater than atmospheric, and at a temperature of approximately 280 to 300 degrees F. to dissolve and separate emulsifying constituents before any substantial oxidation can take place.

10 Therefore, it is an essential step of this invention to prevent any air contact with the lubricating oil stock or distillate prior to this treatment with potassium hydroxide.

15 The separated treated lubricating oil stock after the treatment under steam pressure with the water solution of potassium hydroxide is treated with acid at the rate of approximately $\frac{1}{2}$ to as high as 1 pound or a little higher, of 66 degree Baumé sulphuric acid per gallon of oil, by methods well-known in the art.

20 The acid-treated oil separated from the acid reaction products, is then subjected to a neutralization operation consisting in commingling the oil with calcium hydroxide and an adsorbent clay at a temperature of approximately 300 degrees F., after which the treated oil is separated from the calcium hydroxide and adsorbent clay containing the adsorbed constituents, this operation being 25 conducted in accordance with the pending application of John C. Black, Wirt D. Rial and Raymond T. Howes, Serial No. 104,836, filed April 26, 1926, process of purifying petroleum oils, granted October 10, 1928, Patent No. 1,709,203 of April 16, 1929.

25 The lubricating oil stock, after the aforesaid treatments, is again re-distilled at a reduced pressure and finally clarified and decolorized to the required degree by methods known in the art, preferably commingling the re-distilled oil with the clarifying and decolorizing agent at a temperature of approximately 300 degrees F.

30 While the process herein described is well adapted for carrying out the object of the invention, it is to be understood that various changes and modifications may be made without departing from the spirit of the invention, and the invention includes all such changes and modifications as come within the scope of the appended claims.

35 What I claim is:

1. That step in the process of refining lubricating oil stocks, comprising, separating by 40 vacuum distillation a lubricating oil stock from an asphalt or mixed base crude petroleum oil, continuously and immediately with the exclusion of air condensing and re-distilling the lubricating oil stock as produced, continuously condensing the re-distilled lubricating oil stock with the exclusion of air and immediately treating the same in liquid phase with a water solution of potassium hydroxide in the presence of steam to separate the oxidizable constituents therefrom.

2. That step in the process of refining lubricating oil stocks, comprising, separating by vacuum distillation a lubricating oil stock from an asphalt or mixed base crude petroleum oil, immediately with the exclusion of air condensing and re-distilling the lubricating oil stock as produced, condensing the re-distilled lubricating oil stock with the exclusion of air and immediately treating the same in liquid phase with a water solution of potassium hydroxide in the presence of steam to separate the oxidizable constituents therefrom.

70 In testimony whereof I affix my signature.

WIRT D. RIAL.
